JACOB RUPERT SCOTT, OF NORTH WEYMOUTH, MASSACHUSETTS, ASSIGNOR OF TWO-TENTHS TO EDWARD H. KAVANAGH AND TWO-TENTHS TO JAMES W. COLGAN, BOTH OF WEYMOUTH, MASSACHUSETTS.

AIR-HEATER FOR INTERNAL-COMBUSTION ENGINES.

1,276,124.

Specification of Letters Patent. Patented Aug. 20, 1918.

Application filed January 2, 1917. Serial No. 139,993.

To all whom it may concern:

Be it known that I, JACOB RUPERT SCOTT, a citizen of the United States, and resident of North Weymouth, county of Norfolk, State of Massachusetts, have invented an Improvement in Air-Heaters for Internal-Combustion Engines, of which the following description, in connection with the accompanying drawing, is a specification, like characters on the drawing representing like parts.

This invention relates to improvements in air heaters for internal combustion engines and the general object thereof is to provide a simplified means for more effectively vaporizing the liquid fuel and supplying the vaporized mixture to the engine.

A further object of the invention is to provide a fuel supplying and vaporizing device which will obviate the necessity for a complicated and expensive carbureter by vaporizing the fuel by a current of hot air caused to impinge directly upon one or more jets of liquid fuel.

Another object of the invention is to provide a vaporizing device of the character described in which the supply of liquid fuel and air will at all times be proportionate to the demand of the engine under all usual running conditions.

A further feature of the invention comprises a novel means for heating the air in the intake pipe, delivering the heated current of air to the fuel feeding chamber whereby complete vaporization of the fuel will be effected.

Other objects and features of the invention and the nature thereof will more fully appear from the following description and the accompanying drawings and will be particularly pointed out in the annexed claims.

The drawings illustrate my invention as applied to an automobile engine of a usual type, but it is to be understood that the invention may be incorporated in any other suitable type of internal combustion engine.

In the drawings;

Figure 1 is a side elevation of a conventional six-cylinder automobile engine with my invention applied thereto,

Fig. 2 is an end view of the same showing my improved liquid fuel vaporizing device and the air heating means, mainly in section,

Fig. 3 is a detail sectional view of a portion of the air intake and its relation to the exhaust conduit through which the hot products of combustion are discharged from the engine, and.

Fig. 4 is a vertical sectional view on a larger scale, of the vaporizing or feeding chamber and the exhaust conduit placed in juxtaposition to illustrate more clearly the vaporizing mechanism and the manner in which the air is heated by the products of combustion and delivered to the same.

In usual types of internal combustion engines a carbureter of more or less complicated and expensive construction is utilized to vaporize the liquid fuel and to mix the same with the necessary amount of air to produce an explosive charge for the engine, means usually being provided whereby the operator may regulate the supply of liquid fuel so that a more or less rich mixture may be supplied to the engine according to its demands. The present invention contemplates the provision of simple automatically operable means responsive to the suction of the engine for supplying both the amount of liquid fuel and the amount of air required to form the proper mixture at each intake stroke of the engine so that the engine may be controlled entirely by the usual throttle valve under all ordinary running conditions.

A preferred embodiment of my invention is illustrated in the accompanying drawings as applied to a usual form of six-cylinder automobile engine comprising a crank case 1 having a driving shaft 2 journaled therein and supporting the usual pairs of cylinders 3, 4, 5, each cylinder being, of course, provided with a piston connected to the crank shaft in the usual manner (not shown).

The cylinders may be and are equipped with the usual inlet and exhaust valves, which are conventionally illustrated herein as spring actuated valves 6. The explosive mixture is supplied through the manifold 7 and the products of combustion are carried away by the common exhaust conduit 8 as is common in engines of this type. Any desired ignition system may be used, the electric conductors for the same being comprised in the cable 9.

The simplified means for supplying the explosive mixture to the cylinders preferably comprises a tubular casing 10, con-

nected at its upper end to the lower end of the downwardly extending trunk 11 of the manifold 7 and having a spray pipe 12 extending through its otherwise closed lower end 13 and having jet apertures located at a distance above said bottom and an air intake conduit 14 leading through its side in proximity to the upper end of the spray pipe 12.

10 The casing desirably has a circumferential flange 15 at its upper end which may be secured to a corresponding flange 16 at the lower end of the manifold trunk, and a screen 17 of finely meshed wire preferably 15 is clamped between the abutting ends of the manifold trunk and casing. The screen 17 serves the double function of preventing dust or other soiled matter from being drawn into the cylinder and causing the 20 vapor laden air to eddy in the lower part of the casing so that the molecules of vaporized fuel are more intimately mixed with the molecules of oxygen in the air.

The lower end of the casing preferably is 25 contracted to form a boss 18 and is apertured to receive the spray pipe 12. The lower part of the aperture is enlarged and its walls screw threaded to form a stuffing box and a suitable packing is retained 30 tightly therein by a nut 19 screwed into the lower end of the boss. The upper end of the spray pipe 12 desirably is closed by a screw plug 20 and is provided with jet apertures 21 just beneath the plug 20, said jet 35 apertures being at a considerable distance from the bottom of the casing. By reason of this construction the lower end of the casing forms a receptacle for any excess of fuel which may be drawn from the spray 40 pipe 12 and the eddying of the air in the lower part of the casing 10 will serve gradually to vaporize the fluid from the pool thus formed.

The lower end of the spray pipe, as illustrated herein, is connected by a detachable union 24 to a supply pipe 25 which preferably leads to a closed supplemental reservoir 26. By reason of this construction the spray pipe 12 may readily be removed from 50 the casing 10 for the purpose of cleaning or to substitute another tube having jet orifices of different size for the purpose of correlating the fuel supply to the amount of air taken in by the suction of the engine.

55 The supply pipe 25 may extend directly into the reservoir but may conveniently be made in sections connected by an L shaped union having a priming cup 27 and the lower end of said pipe is provided with a ball valve 28 and screen 29. Fuel is supplied to the supplemental reservoir 26 through a pipe 30 leading from the main fuel tank 31, which may be located in any convenient portion of the vehicle. It will 60 however be understood that the supplemen-

tal reservoir may be omitted and the fuel supply pipe 25 connected directly to the main fuel tank 31.

In order to facilitate starting the engine a priming cup 32 may be connected to the 70 side of the casing 10 so that a priming charge may be injected directly into the feeding chamber within said casing.

The usual butterfly throttle valve 33 is 75 pivotally mounted in the upper portion of the casing 10. The pivotal axis of said valve is provided with an arm 34 which is operated by the usual lever located in convenient reach of the operator.

In the operation of the machine the suction of the engine draws fine jets, which form a spray, through the orifices 21 in the upper end of the spray pipe 12, the amount of fuel thus delivered being proportionate to the vacuum created by the successive intake strokes of the several pistons, that is, the amount of fuel supplied to the feeding chamber is in exact proportion to the demands of the engine, subject of course to the control of the throttle valve which may 90 be manipulated at will by the operator.

The air required to form an explosive mixture is supplied to the feeding or vaporizing chamber through the intake conduit 14, which, as heretofore stated, leads 95 through the casing 10 in proximity to the upper end of the spray pipe 12. The air intake pipe extends to the exhaust conduit and desirably has a section 35 which passes through a portion of the exhaust conduit 100 and is directly heated by the hot products of combustion.

The exhaust conduit is provided with a longitudinally extending aperture, the marginal walls of which are provided with 105 flanges 36 to which are secured flanges 37 on the walls of a hollow casing 38 which forms a heating chamber communicating freely with the exhaust conduit.

The section 35 of the intake pipe extends 110 through the end walls of this heating chamber and the ends of said intake pipe section 35 preferably are connected to mouth pieces 39, the intake ends of which are shaped to conform to the contour of the outside of the 115 exhaust conduit and are located in proximity thereto.

The open ends of the mouth pieces are covered with fine gauze to exclude dust and other solid substances. By reason of this construction the radiation from the exhaust conduit normally tends to direct the dust from the mouth of the intake pipe.

In operation the air is drawn by the suction of the engine into the mouth pieces of 125 the intake pipe, and, as the intake openings therein lie in close proximity to the wall of the exhaust conduit, is heated to some extent as it enters. It then passes through the section 35, which is within the heating 130

chamber and is normally maintained by the hot products of combustion at about a red heat, and is very highly heated. It passes thence into the feeding or vaporizing chamber where it impinges directly upon the spray of liquid fuel which is delivered through the spray jets 21 and being at such a high temperature quickly vaporizes said fuel and forms with it a perfect mixture as it passes through the screen 17 into the manifold and thence to the cylinders.

The intake pipe 14 may be made of such size for any particular type of engine that it will deliver the proper amount of air to vaporize completely the amount of fuel supplied for any usual running condition, the size of the pipe 14 and the size of the jet apertures being correlated to the demand of the engine for usual running conditions. I have found that an engine having a $3\frac{3}{4}$ inch exhaust pipe and a heating chamber $2\frac{1}{2}$ inches in diameter and twelve inches long with an intake conduit having a diameter of $1\frac{1}{2}$ inches delivering to a feeding chamber $5\frac{1}{2}$ inches long and $2\frac{1}{2}$ inches in diameter equipped with a spray pipe $\frac{3}{8}$ inch in diameter and having two jet orifices $\frac{1}{2}$ inch in diameter each will supply a perfect mixture which will drive a forty horsepower seven passenger car at any desired speed up to fifty miles per hour under the control of the throttle valve above described without manual regulation of the supply of fuel or the air supply.

While intake pipes of different sizes may be necessitated for different types and sizes of engine the proper size pipe may be selected with but a slight amount of experimentation and the size of the orifices in the fuel pipe to supply the proper amount of liquid may also readily be determined in the same manner.

In order to facilitate starting of the engine a valve 41 may if desired be placed in the air pipe 14 and its pivotal stem 42 provided with an arm 43 connected to a suitable controlling lever (not shown) in convenient reach of the operator. In starting the engine this valve may be closed so that the suction of the engine, when turned over, will draw a small amount of fuel into the feeding chamber to form the initial charges. As soon as the engine has started the valve 41 may be opened, whereupon the supply of air and fuel will automatically respond to the requirements of the engine as aforesaid. If it is desired to supply a richer mixture to the engine than that which is normally delivered by the intake pipe when fully opened, it may be accomplished by actuating the throttle valve 41 to restrict the flow of hot air through the air intake pipe.

When the jet apertures 21 and the air intake pipe are properly proportioned to deliver the required amount of fuel and air

to make a perfect mixture there is, of course, no need of manipulating the butterfly valve 41 in the air intake pipe and I have also found that there is no necessity for changing the relative proportions of the jet apertures and the air intake pipe for differences of climate, location or altitude, so that the main function of the butterfly valve in the air intake pipe is to facilitate the starting of the engine in the manner above described.

I have found that an engine embodying my invention is far more economical than when equipped with a usual high grade carburetor and that its operation is more uniform and certain.

While I have illustrated my invention embodied herein in an automobile engine it will be understood that the invention is adapted to be applied to any usual type of internal combustion engine and that various changes in the form of construction to adapt the same to other types of engines may be made within the scope of the following claims.

Having thus described my invention what I claim as new and desire to secure by Letters Patent is:

1. In an internal combustion engine comprising a plurality of cylinders, an intake manifold leading to said cylinders, a mixing chamber communicating with said manifold and means for supplying liquid fuel to said mixing chamber; an exhaust manifold leading from said cylinders having a lateral extension forming a heating chamber, a heating pipe extending through said chamber provided at its end with a bell shaped mouth piece lying close to and conforming to the contour of said manifold, an air intake pipe connecting with said heating pipe and leading to said mixing chamber.

2. In an internal combustion engine comprising a plurality of cylinders, an intake manifold leading to said cylinders, a mixing chamber communicating with said manifold and means for supplying liquid fuel to said mixing chamber; an exhaust manifold leading from said cylinders having a lateral extension forming a heating chamber, a heating pipe extending through said heating chamber and having its ends open to the atmosphere, an air intake pipe extending into said heating chamber communicating with said heating pipe within said chamber and leading therefrom to said mixing chamber.

3. In an internal combustion engine comprising a plurality of cylinders, an intake manifold leading to said cylinders, a mixing chamber communicating with said manifold and means for supplying liquid fuel to said mixing chamber; an exhaust manifold leading from said cylinders having a lateral extension forming a heating chamber, a heating pipe leading through said chamber in parallelism with said intake manifold and

provided at both ends with downwardly extending bell shaped mouth pieces curved to conform to the contour of the manifold and lying closely adjacent thereto and an air intake pipe extending into said heating chamber connecting centrally with said heating pipe and leading therefrom to said mixing chamber.

4. In an internal combustion engine comprising a plurality of cylinders, an intake manifold leading to said cylinders, a mixing chamber communicating with said manifold and means for supplying liquid fuel to said mixing chamber; an exhaust manifold lead-

ing from said cylinders having a longitudinal opening therein, a semi-cylindrical casing detachably secured to said manifold providing an auxiliary heating chamber, a heating pipe extending longitudinally of said heating chamber open at both ends to the atmosphere, an air intake pipe extending into said heating chamber and communicating with said heating pipe and leading therefrom to said mixing chamber.

In testimony whereof, I have signed my name to this specification.

JACOB RUPERT SCOTT.
